UNITED STATES PATENT OFFICE.

CHRISTOPHER HATFIELD, OF NEW YORK, N. Y.

DESIGN FOR A LAMP-STAND.

40,604.

Specification for Design.

Patented Apr. 5, 1910.

Application filed February 7, 1910. Serial No. 542,656. Term of patent 3½ years.

To all whom it may concern:

Be it known that I, CHRISTOPHER HATFIELD, a citizen of the United States, and residing in the borough of Brooklyn, in the county of Kings, in the city and State of New York, have invented a new, original, and ornamental Design for Lamp-Stands, of which the following is a specification, reference being had to the accompanying drawing, which forms a part thereof.

The drawing is a perspective view of a lamp stand showing my new design.

What I claim is.—

The ornamental design for a lamp stand as shown.

CHRISTOPHER HATFIELD.
